THERAPEUTIC COMPOSITION OF
SULFONAMIDESClair E. Folsome, Plainfield, N. J., assignor to
Ortho Pharmaceutical Corporation, a corpora-
tion of New JerseyNo Drawing Application June 8, 1946,
Serial No. 675,325

1 Claim. (Cl. 167—51.5)

1 This invention relates to novel compositions of matter and more particularly those finding application in the therapeutic field. In its more specific aspects, the invention is directed to novel compositions especially useful as gynecic products which may be applied topically.

It has been known that (a) abnormal bacterial flora in the vagina of an expectant mother provides a hazard in the form of an infection of the lining or wall of the uterus which infection might progress to such a stage as to become a general peritonitis which may ultimately reach such a condition as to cause death from a septicemia; (b) abnormal bacterial flora in the vagina particularly the anaerobic streptococci whose end products of protein metabolism are highly objectionable because these end products have a characteristically disagreeable odor and produce an objectionable condition during the healing process following minor cervical surgery, such as cauterization and conization as well as following major cervical surgery, such as hysterectomy; (c) abnormal bacterial flora in the vagina sometimes interferes with the normal healing process following minor cervical surgery, such as, cauterization or conization to correct cervical erosion and/or endocervicitis and following major surgery, such as hysterectomy.

Prior to this invention it has been proposed to treat various forms of vaginitis with a topical medicament containing a sulfonamide. The sulfonamide generally proposed for this purpose has been the well known "sulfa" compound, known as sulfanilamide. The medicament containing said sulfanilamide has not been satisfactory, mainly because its pK_a value is outside of the range of 3.5 to 8 which is the pH range of the culture medium in the vagina. As pointed out in the table on page 2906 of Journal of American Chemical Society, volume 64, #12, 2905-2917, December 1941, in the article by Bell and Roblin, the pK_a value of sulfanilamide is 10.43. Philip B. Cowles in the Yale Journal of Biology and Medicine, volume 14, pages 599-604, July 1942, has established that in general the bacteriostatic power of a sulfonamide is at its maximum when its pK_a approximates the pH of the culture medium and decreases progressively as the pH of the medium departs in either direction from that pH.

In the course of my experimentations with the various sulfonamides, I have discovered that an effective medium for controlling the aforesaid abnormal bacteria flora could be provided. For this purpose, I have provided a plurality of sulfonamides whose pK_a values differ at least by 1 and for example are between 6 and 8 and 4 and 6, and preferably three of them, one having a pK_a between 6 and 8, one having a pK_a between 5 and 6 and another having a pK_a between 4 and 5. Of the number of sulfonamides available, I pre-

2 fer the combination of sulfathiazole, N^1 acetyl-sulfanilamide and N^1 benzoylsulfanilamide. By employing these particular sulfonamides in combination, I have provided a medicament whose bacteriostatic activity is at least 80% of maximum activity of the individual sulfonamides over a pH range of 3.5 to 8 which is the pH of the culture medium within the vagina depending on the condition of the vagina at any particular time. This combination is particularly effective because during the reparative process of healing in a vagina with a pH of about 8, there is a regression of the pH to a value of 3.5 to 4. And, these particular sulfonamides have maximum bacteriostatic action at pK_a 's of approximately 7, 5.5 and 4.5 respectively. Sulfathiazole shows at least 80% of maximum bacteriostatic activity in the pH range of 6 to 8, N^1 acetyl-sulfanilamide in the pH range of 4.5 to 6.5 and N^1 benzoylsulfanilamide in the pH range of 3.5 to 5.5. In addition, I have discovered that by using this particular combination, there is less cumulative absorption and more pronounced local tissue action than with sulfathiazole alone in the same concentration. While the ratio of these sulfonamides may vary, I prefer that they be present in a mixture in which the molar ratio of these three components is approximately 1 to 1 to 1.

They are preferably in such comminuted form that the particle size thereof is no greater than 4 microns. For my purposes the particle size of said sulfonamides may be in the range of 0.1 to 4 microns so as to eliminate irritation of wound surfaces with consequent retardation of wound healing and the production of local area of chemical irritation producing scar tissue if large particles or crystals of the sulfonamides were employed.

While said plurality of sulfonamides may be employed without any further additions, it is preferable to combine therewith urea peroxide which serves to reduce the sulfonamide inhibiting activity of such compounds as p-amino-benzoic acid and methionine normally present in body fluids and exudates at wound surfaces, and also because urea reduces the tendency of sulfonamides to injure the kidneys by preventing crystal growth. Urea peroxide in said combination has the added function of acting as a bactericidal agent complementing the sulfonamides in their therapeutic action. A still further function of the urea peroxide is that it sterilizes the finished product as it leaves the manufacturing assembly.

For my purposes, I prefer to employ a combination of a plurality of sulfonamides whose pK_a values are in the range of 3.5 to 8 and whose combined bacteriostatic action over the entire pH range of 4 to 7.5 is at least about 70% of the maximum bacteriostatic action of an individual sulfonamide at the most favorable pH therefor. 60 This combination is preferably free of any sul-

fonamide whose pKa is outside of the range of 2.5 to 9.

While the various combinations of this invention may be applied in the form of dry powder or in solution, I prefer to incorporate them in a water soluble or dispersible vehicle in which the active ingredients are readily and easily available. The vehicle should preferably possess a degree of tackiness thereby making it an aesthetically acceptable preparation which will not leak out of the vagina, making it unnecessary for the patient to use a sanitary napkin for more than minimal period during which lymph and other fluids might be escaping from the wound surfaces.

For this purpose, I prefer to employ an oil in water dispersion as a vehicle. Among vehicles of this type, which may be employed are those known as "vanishing creams" examples of which are herein given merely by way of illustration, and all parts being given by weight.

Vanishing cream—Example I

Stearic acid	16
Potassium hydroxide	1
Glycerine	6
Water	73

Vanishing cream—Example II

Stearic acid	4
Spermacetic	4
Glyceryl monostearate	10
Potassium hydroxide	.12
Water	81.88

Into the oil in water vehicle may be uniformly distributed a plurality of sulfonamides and preferably the three component sulfonamide combination without, but preferably with, said urea peroxide. The ratio by weight of said three component sulfonamide combination to said vehicle may be in the range of about 3 to 100 and 12 to 100. The ratio by weight of the urea peroxide to the combined weights of the sulfonamides may be in the range of about 1 to 10 and 1 to 2.

The following is a specific and preferred example illustrating the active components and ratio of active components in an oil in water base, all parts given by weight.

Example III

Sulfathiazole	3.4
N ¹ acetyl sulfanilamide	2.86
N ¹ benzoyl sulfanilamide	3.7
Urea peroxide	1
Base (oil in water dispersion)	89.04

Clinical experience with compositions embody-

ing the present invention has shown that by employing them as topical vaginal medicaments the post-operative and post-conization leucorrhoeas may be reduced by nearly two-thirds and in addition mucosal healing and the reversion to the four normal physiological balances may be accomplished within a period of 12 to 21 days in contrast to the usual 42 to 56 days.

The compositions of the present invention are particularly useful in those vaginal conditions caused by the overgrowth of secondary bacterial invaders in the presence of broken down tissue. They have been found to be especially efficacious in the following vaginitides:

- 15 1. Post-operative vaginitis or cervicitis.
2. Post-cauterization of cervix.
3. Chronic adhesive vaginitis.
4. Ulcerative vaginitides.
5. Post-radiation vaginitis and cervicitis.
- 20 6. Post-conization cervicitis.
7. Antepartum vaginitis and cervicitis.
8. Postpartum vaginitis and cervicitis.

Dosages of about five grams of the composition shown in Example III, twice daily during the more serious extent of the condition and reducing the dose to one half to one quarter after 4 to 6 days, have been particularly effective.

I claim:

- 4 30 1. A multiple sulfonamide therapeutic composition, for topical application showing synergism due to the differences in pKa values of the sulfonamides present, comprising substantially equimolar proportions of two and only two members of the group consisting of N¹-acetyl sulfanilamide, N¹-benzoyl sulfanilamide, and sulfathiazole.

Certificate of Correction

Patent No. 2,491,489

December 20, 1949

CLAIR E. FOLSOME

It is hereby certified that errors appear in the printed specification of the above numbered patent requiring correction as follows:

Column 1, lines 40 and 41, for "December 1941" read *December 1942*; column 2, line 6, for "indivdual" read *individual*; line 17, for the words "activity is" read *activity in*;

and that the said Letters Patent should be read with these corrections therein that the same may conform to the record of the case in the Patent Office.

Signed and sealed this 18th day of April, A. D. 1950.
